United States Patent Office

Des. 184,993
Patented Apr. 28, 1959

184,993

SOFA

Margaret M. Foulkes, Little Falls, N.J.

Application November 10, 1958, Serial No. 53,304

Term of patent 14 years

(Cl. D15—11)

Fig. 1

Fig. 2

Fig. 5

Fig. 1 is a front perspective view of a sofa embodying my design, the view being taken from one end of the sofa;

Fig. 2 is a similar view taken from the other end of the sofa; and

Fig. 3 is a rear perspective view thereof, the view being taken from the same end of the sofa as Fig. 2.

I claim:

The ornamental design for a sofa, as shown.
